US00D762333S

(12) **United States Design Patent**
Pulliam et al.

(10) **Patent No.:** **US D762,333 S**
(45) **Date of Patent:** **** Jul. 26, 2016**

(54) **ELECTRONIC MODULE FOR A DOG COLLAR**

(71) Applicant: **i4C Innovations Inc.**, Chantilly, VA (US)

(72) Inventors: **Graham Pulliam**, Washington, DC (US); **Jonathan Abarbanel**, Los Angeles, CA (US); **Jeffrey Bentzler**, Playa Del Rey, CA (US); **John Michael Couse**, Toronto (CA); **Emily Hartman**, Purcellville, VA (US); **Stuart Karten**, Venice, CA (US); **Amanda Landis-Hanna**, Fairfax, VA (US); **Frederick Joel Mason**, Haymarket, VA (US); **Jeffrey Noce**, Alexandria, VA (US); **Joe Paul Tupin, Jr.**, Round Hill, VA (US); **Wendy L. Weinberger**, Ashburn, VA (US)

(73) Assignee: **i4c Innovations Inc.**, Chantilly, VA (US)

(**) Term: **15 Years**

(21) Appl. No.: **29/536,436**

(22) Filed: **Aug. 17, 2015**

(57) **CLAIM**

The ornamental design for an electronic module for a dog collar, as shown and described.

DESCRIPTION

FIG. 1 is a front perspective view of an electronic module for a dog collar showing our new design.

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

1 Claim, 4 Drawing Sheets
